UNITED STATES PATENT OFFICE.

CHARLIE B. WILSON, OF TAMPA, FLORIDA.

TRAY FOR INCUBATORS AND BROODERS.

Application filed February 3, 1921. Serial No. 442,125.

To all whom it may concern:

Be it known that CHARLIE B. WILSON, a citizen of the United States, residing at Tampa, in the county of Hillsborough and 5 State of Florida, has invented certain new and useful Improvements in Trays for Incubators and Brooders, of which the following is a specification, reference being had therein to the accompanying drawings.

10 This invention relates in general to improvements in incubators and brooders, and has for its object the construction of a tray that is provided with means for providing an even heat so that the eggs or chickens 15 carried thereby will not become chilled under ordinary conditions.

Another object of the invention is the construction of a tray which gathers and retains heat so that the chickens or eggs carried thereby will not readily become chilled, 20 which means is also provided for preventing overheating the eggs or chickens.

With these and other objects in view, my invention comprises certain novel combinations, constructions and arrangements of parts as will be hereinafter described, illustrated in the accompanying drawings, and more particularly pointed out in the appended claim.

30 In the drawings:

Figure 1 is a top plan view of an incubator constructed in accordance with the present invention.

Figure 2 is a view in side elevation of 35 the incubator.

Figure 3 is a sectional view, taken on line 3—3, Fig. 1, and looking in the direction of the arrows.

Figure 4 is an end view, in elevation, of 40 the incubator, looking at the end to which the heating apparatus is connected.

Figure 5 is a sectional view, taken on line 5—5, Fig. 3, and looking in the direction of the arrows.

45 Figure 6 is an enlarged fragmentary sectional view, taken on line 6—6, Fig. 1, and looking in the direction of the arrows.

Referring to the drawings by numerals, 1 designates the body of the incubator, and 2 50 are the legs supporting the same. The body has an inner lining 3 spaced therefrom between which inner lining and the outer lining a compartment 4 is formed that may contain hot air but preferably is for hot 55 water.

The heating apparatus comprises a tank 5, into the central part of which extends the chimney 6 of the lamp 7, and the tank 5 is connected by tube 8 to the top of the body 1 and by the curved tube 9 to the body near 60 its bottom; these tubes 8 and 9 provide means for permitting water in the tank and body of the incubator to circulate, while heated by the lamp 7.

A cap 10 is provided for filling the compartment 4.

A hollow hinged door 11 is formed upon the top. The front door 15 is hinged upon the body 1 of the incubator and this door has glass in the same as usual, so that eggs 70 can be easily seen upon the tray 16. The young chicks can also be seen through the front door 15.

The tray 16 rests upon angular brackets 17, each bracket being provided with a horizontal foot 18.

75 The tray 16 comprises a false bottom 19, in which bottom is compartment 20, the compartment being filled by a liquid or water by the removal of the cap 21. A strip 80 of felt 22 is placed upon the false bottom and the upper section 23 of the tray, containing the eggs 24, is placed upon the felt 22; the false bottom, felt and upper section or container 23 can be securely fastened together by any suitable means. The felt 22 prevents too much heat affecting the eggs 24 and by reason of the closed bottom of the tray air is kept from rushing up through the bottom and by the eggs, which would 90 tend to unnecessarily cool them or harden the shell during incubation.

95 It will be obvious that young chickens can remain on the tray 16, without injury, until the operator removes same by opening the door 15.

The means for controlling the temperature of the incubator comprises a coil thermostat 25 mounted upon lug 26 attached to the inner wall of the incubator, Fig. 6. The 100 outer loop or coil of the thermostat terminates in a vertical rod 27, which rod extends through the pipe 28 and above the top of the incubator, or brooder, as this thermostat and damper device is applicable to 105 both the incubator and the brooder. The extended upper end of the rod 27 is threaded and upon this threaded end are a pair of nuts 29. Between these nuts 29 are the loop ends 30 of the flame cut-off lever 31 and 110

the damper lever 32. The levers 31 and 32 are pivotally mounted in the notched upper ends or angle brackets 33. The damper lever is connected, at its upper end, to the 5 damper 34, which damper 34 closes the heat compartment 35 of the tank 5.

The flame cut-off lever 31 is provided with a vertical extension 36, which extension 36 is pivotally connected, at its lower 10 end, to arm 37 of the rocking frame 38, which frame is of an open structure being formed of wire; the frame 38 is adapted to straddle or move over the wick 39 of the lamp 7 and cut out or extinguish the flame, 15 as shown by dotted lines 40 in Fig. 3, when the temperature becomes too great in the incubator, causing the expansion of the thermostat 35 and the shoving up of the rod 37, thereby permitting the levers 31 and 32, 20 at their outer ends, to move downwardly, causing the closing of the damper 34 and the swinging of the rocking frame 38 to cut off or put out the flame 39. This will result in the stopping of the heating of the 25 liquid in the tank, but by reason of the damper 34 being closed, the heat in the tank will only slowly be given off, thereby retaining the heat in the whole apparatus a very long time sufficient to allow the operator 30 to discover that the light is out or extinguished, or permit the lighting of the lamp before any harm has been done.

As hereinbefore indicated, my incubator can be easily adapted to the use of a brooder, by the chickens remaining on the tray 16, or by placing in any suitable floor on the bracket 17 to keep the chickens off the inner lining 3. I make no claim to the flooring that would entirely fill the space 40 and prevent the chickens from dropping onto the lining 3, but this flooring can be

easily inserted in the body 1, without involving invention.

The pipe 41 (Fig. 3) extends through the side of the body 1, its inner end projecting 45 into the inner compartment of the body and its outer end extending beyond the outer surface of the body, so that the outer atmosphere will enter the compartment, containing eggs or chicks, allowing the right degree of moisture or a similar quantity of 50 fresh air to enter the chamber and thereby keeping the conditions in the chamber sanitary, the air being purified by the medium of the pipe 41.

While I have described the preferred structure of my apparatus, and have illustrated the same in the accompanying drawings, certain minor changes or alterations can be made by one skilled in the art to 60 which this invention relates, in the manufacture of my apparatus on an enlarged scale and I, therefore, reserve the right to make such alterations or changes as shall fairly fall within the scope of the appended 65 claim.

What I claim is:

As an article of manufacture, a tray for an incubator or brooder comprising a substantially flat hollow bottom, thereby forming a compartment within said bottom, a liquid filling means mounted upon said bottom, a flat heat insulating sheet permanently fixed upon the upper surface of said bottom, and a sheet metal egg or chick containing upper 70 section fixed upon said sheet, thus forming a unitary structure for use in conventional types of incubators and brooders.

In testimony whereof I hereunto affix my signature.

CHARLIE B. WILSON.
